FAN BLADE

Arthur E. Kline and Wendell H. Webster, Albion, Mich.,
assignors, by mesne assignments, to McGraw Electric Company, a corporation of Delaware

Application April 6, 1953, Serial No. 24,363

Term of patent 14 years

(Cl. D26—7)

Fig. 1 is a front perspective view of a fan blade showing our new design; and

Fig. 2 is a front elevational view of the same.

We claim:

The ornamental design for a fan blade, substantially as shown.
